AIRCRAFT

Paul M. Lewis and Fred Landgraf, Denver, Colo.,
assignors to Lewis-American Airways, Inc., a
corporation of Colorado

Application April 20, 1933, Serial No. 666,947

9 Claims. (Cl. 244—16)

This invention relates to an improved air craft and more particularly to improved lifting and propelling surfaces for air craft.

The principal object of the invention is to provide rotatably mounted blades or wings for aircraft which can be regulated while in use to exert either or both a lifting and propelling action.

Another object of the invention is to provide a simple and efficient mechanism which will automatically change the pitch of rotating wings or blades during their revolution so that the ascending blades will have a different effect than the descending blades.

A further object of the invention is to provide an efficient and positive manual control for the automatic pitch changing mechanism so that the pitch of the blades to which the automatic mechanism operates can be varied at the will of the operator.

A still further object of the invention is to efficiently incorporate the above type of rotating blades with an aircraft.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:—

Fig. 1 is a perspective view illustrating an air craft, in which the invention is embodied, as it would appear in flight.

Fig. 2 is a detail view looking downwardly on a set of the blades as they pass the uppermost point of their revolution or vertical position.

Fig. 3 is an end view of the rotating blades as they would appear when in the horizontal position with their pitch adjusted for both lifting and propelling.

Fig. 4 is a similar view with the blades as they would appear when adjusted exclusively for propelling.

Fig. 5 is a plan view of the hub portion of one set of the blades. In this view the blades are adjusted as shown in Fig. 3.

Fig. 6 is a front view of the hub portion illus-

trating an alternate method for adjusting the action of the blades.

Fig. 7 is a longitudinal section through the form of Fig. 6, taken on the line 7—7, Fig. 6.

Fig. 8 is a horizontal section taken on the line 8—8, Fig. 7.

The invention embodies one or more pairs of rotatably mounted wings or blades which may be mounted in any desired position on any desired style or type of air craft. One method of employing the present invention is illustrated in Fig. 1, in which a fuselage is indicated at 10, provided with upwardly-extending, outwardly-flaring struts 11. The struts support a series of pairs of rotating blades 12 and 12' which replace the usual air plane wings. A horizontal control shaft 14 extends between the hub portions of the front pairs of blades and a similar control shaft 14' extends between the hub portions of the rear pairs. The control shafts 14 and 14' are operated from suitable controls in the fuselage 10 through the medium of connecting rods 45 extending from operating levers 46.

The hub construction is such that when the forward operating lever 46 is forced upwardly, as illustrated in Fig. 1, the downwardly moving blades will assume a relatively horizontal position and the upwardly moving blades will assume a relatively vertical position. These relative positions will be maintained during the rotation of the blades so that each blade as it passes the bottom point will turn toward the vertical and as it passes the top point will turn toward the horizontal. The blades may be rotated through any desired transmission device from a suitable motive power.

Each pair of blades is similar in construction and for convenience in description, the downwardly moving blades will be designated by the numeral 12 and the upwardly moving blades by 12'. Each pair of blades 12 and 12' is mounted on a common blade shaft 13 in planes at right angles to each other.

The preferred construction for causing the blades to assume their relative positions during rotation is illustrated in detail in Figs. 3, 4, and 5. In this construction, the blade shaft 13 of each pair of blades passes through a pair of spaced apart bearings 15 in a rotating bracket member 16 which is secured on the extremity of 50

a drive shaft 17. If two pairs of blades are employed, as illustrated, one of the brackets 16 will be secured on each extremity of each drive shaft 17. The drive shaft may be driven in any desired manner. As illustrated, it is driven through a pair of bevel gears 18 from the extremity of a power shaft 19 extending through the strut 11 from the fuselage. It can be readily seen that as the drive shaft 17 rotates, it will rotate the brackets 16 and, through the bearings 15, will swing the blades 12 in a vertical plane about the axis of the drive shaft in a circular arc.

A pair of studs 20 project oppositely outward from the middle of the blade shaft 13 to engage the furcations of a bifurcated yoke 21. Thus, when the blade shaft is horizontal, it can be rotated by swinging the yoke 21 in a vertical plane to change the angle of incidence or pitch of the blades 12 and 12'. The yoke is provided with an outwardly extending stem 22 which is rotatably mounted in a bearing or journal 23 on the extremity of the blade control shaft 14. Thus, as the control shaft 14 is rotated, it will swing the yoke 21 vertically to change the blade angle. Since the control shafts 14 are horizontal and fixed to the journals 23 they will, of course, swing the yokes 21 only in vertical planes. As before stated, the blades 12 and 12' are mounted on the blade shaft at right angles to each other. The yoke studs 20 are so positioned that the axis of the journal 23 will bisect the angle between the blades as illustrated. On the forward pair of blades the journals 23 will project forwardly from the forward edge of the blades and on the rear pair the journals will project rearwardly between the rear edges of the blades. The journals have a range of vertical angular movement of approximately 45° as indicated by the angle "A", Fig. 3.

With this construction, if the forward journals are adjusted to an upward angle of 45°, the downwardly moving blade 12 on reaching the horizontal position will be substantially horizontal while the upwardly moving blade will be substantially vertical. If we drop the journals, say to an angle of 30°, the rear edge of the downwardly moving blade will be raised and the lower edge of the upwardly moving blade will be swung rearwardly, as illustrated in Fig. 3.

It can be seen that the axis of the yoke studs 20 swings in a plane oblique to the plane of rotation of the blades owing to the angular position of the journals 23. When the blades are horizontal, the yoke axis is of course at its greatest angularity and a maximum twist is imparted to the blades. When the blades are vertical the yoke axis lies in the plane of rotation regardless of the angle of the journal 23 so that no angularity is imparted to the blade shaft and both blades will project at an angle of 45° to the plane of rotation as shown in Fig. 2. As the vertical position of Fig. 2 is passed the formerly vertical blade will assume the horizontal position while the formerly horizontal blade will assume the vertical position.

When the journal is in the horizontal position, both blades will be at a 45° angle and will maintain this angle during their entire revolution so as to exert only a propelling action. If the journal is at any other angle within the angle "A", the downwardly moving blade will always be more horizontal than the upwardly moving blade so as to exert a combined lifting and propelling action on the downwardly moving side, and a propelling action only on the upwardly moving side. If moved to the extreme 45° position, the down-

wardly moving blade will exert only a lifting action and the upwardly moving blade no action whatsoever.

A mechanism for controlling the angular movement of the blades from the drive shaft side thereof is illustrated in Figs. 6, 7 and 8. In this construction, the blade shaft 13 is mounted in spaced apart bearings 25 on the extremities of a forked bracket member 26 that is secured on the extremity of a tubular drive shaft 27. The drive shaft 27 is mounted in suitable bearings 28 and 29, and may be driven in any desired manner as from a bevel gear 30. In this form, the blade shaft 13 is separated at its middle and the two parts are mounted in a frame 31. A yoke 32 is pivoted on oppositely-positioned, axially-aligned yoke pins 33 on the sides of the frame 31. This yoke operates similarly to the formerly described yoke 21 in that any vertical angular position of the yoke will serve to turn the blade shaft 13 as the blades when they are in the horizontal position.

The yoke is swung vertically by means of a rack lever 34. One extremity of the lever 34 extends to a rotatable connection with the yoke 25 and the other extremity is provided with a bevel gear segment 35 which meshes with a bevel pinion 36. Intermediate its extremities, the rack lever 34 is pivoted on a pin 37 in a fork 38 formed on the extremity of a stationary tubular shaft 39 which passes within the drive shaft 27. The shaft 39 is locked in any desired manner such as to the bearing 29 by a set screw 40 so that it can not rotate with the tubular shaft 27 and so that it will always maintain the rack lever 34 in a vertical plane. The pinion 36 is mounted on the extremity of a control shaft 41, extending through the shaft 39 to any desired manual control apparatus such as the crank 42.

It can be readily seen that as the crank 42 is rotated, the yoke 32 will be swung upwardly or downwardly so as to position the yoke 32 at any desired angle to control the rotating blades 12.

It is desired to call particular attention to the unusual action of the present construction. The downwardly moving blades may replace the wings or planes of the usual airplane, as shown in Fig. 1. They differ from the usual planes in that they are inclined downwardly at the front, whereas the usual planes are inclined upwardly. This upward incline of the usual planes places them on what might be termed an upward incline in the air and the motive power must pull the craft up this incline. With the present construction, however, the planes are upon a virtual downward incline in the air, as indicated by the broken line B-B, Fig. 3. Gravity is always tending to pull the planes down this incline, and if the planes were fixed to the aircraft would also pull the craft down.

In the present construction, however, the downward pull of gravity is more than offset by the power driven downward movement of the planes which maintains the aircraft at an even level and allows the pull of gravity to propel the plane forwardly owing to the downward incline of the plane surfaces. Therefore the action of gravity is employed for driving the present plane whereas in the usual conventional plane it acts to resist the motion thereof.

The particular installation of the rotating blades in Fig. 1 employs a rudder 43 for horizontal guiding and ailerons 44 for lifting or lowering the tail of the ship. The lift or descent of the ship is governed by the setting of the angle of

the journals 23 so as to vary the relation between lift and propulsion of the wings 12. The installation of Fig. 1 is simply illustrative since the rotating blades 12 could be employed in any desired installation. They would be valuable as lifting propellers on the conventional airplanes and could be installed on dirigibles for creating both lift and propulsion.

While the blades 12 and 12' have been described as being positioned at angle of 90° to each other, it is to be understood that they are not limited to this exact angle. In some installations it might be desirable to obtain a greater lifting component than driving or vice versa and the relative angle would be arranged accordingly.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A propelling mechanism for aircraft comprising: a drive shaft; a bearing member secured on the extremity of said drive shaft; bearings carried by said member, the axes of said bearings being in alignment and intersecting the axes of said shaft at 90°; a blade shaft mounted in said bearing; a blade-like member carried on each extremity of said blade shaft and extending longitudinally therefrom, said blade-like members being positioned at an angle to each other; means for alternately rotating said blade shaft as said drive shaft revolves so that said blade-like members will be caused to assume a predetermined angle during one part of the revolution and a differing angle during another part of the revolution, said latter means comprising: an actuating member hinged at the mid-point of said blade shaft, the axis of said hinge intersecting the intersection of said blade shaft and said power shaft; and means for maintaining said actuating member at an angle which positions the axis of said hinge in a plane oblique to the plane of revolution of said blades.

2. A propelling mechanism for aircraft comprising: a drive shaft; a bearing member secured on the extremity of said drive shaft; bearings carried by said member, the axes of said bearings being in alignment and intersecting the axis of said shaft at 90°; a blade shaft mounted in said bearing; a blade-like member carried on each extremity of said blade shaft and extending longitudinally therefrom, each of said blade-like members lying in a plane intersecting the axis of said blade shaft yet at an angle to each other; a bifurcated yoke, the furcations of which are hinged to opposite sides of said blade shaft; and means for swinging said yoke in a vertical plane to impart an alternating rotation to said blade shaft during its revolution with said drive shaft.

3. A combined propelling and lifting mechanism for aircraft comprising: a drive shaft; a bearing member secured on the extremity of said drive shaft; bearings carried by said member, the axes of said bearings being in alignment and intersecting the axis of said drive shaft at 90°; a blade shaft mounted in said bearing; a blade-like member carried on each extremity of said blade shaft and extending longitudinally therefrom, said blade-like members being positioned at an angle to each other; hinge members extending oppositely outward from said blade shaft at its mid-point; a bifurcated yoke, the furcations of

which engage said hinge members; a fixed bearing rotatably supporting said yoke at an angle to the projected axis of said drive shaft so as to impart an alternating rotation to said blade shaft during the revolution of said drive shaft.

4. A combined propelling and lifting mechanism for aircraft comprising: a drive shaft; a bearing member secured on the extremity of said drive shaft; bearings carried by said member, the axes of said bearings being in alignment and intersecting the axis of said drive shaft at 90°; a blade shaft mounted in said bearing; a blade-like member carried on each extremity of said blade shaft and extending longitudinally therefrom; hinge pins extending oppositely outward from said blade shaft at its mid-point; a bifurcated yoke, the furcations of which engage said hinge pins; a fixed bearing rotatably supporting said yoke; a controlling member extending from said fixed bearing; and means for actuating said controlling member so as to vary the angle of said fixed bearing with reference to the projected axis of said drive shaft.

5. A combined lifting and propelling device for aircraft comprising: a bearing bracket; a drive shaft secured to, and arranged to rotate, said bearing bracket; oppositely extending blades journaled in said bearing bracket; a frame member connecting said blades; a yoke hinged to the middle of said frame member so as to rotate therewith; a double lever; a stationary member hingedly supporting said double lever within said frame member; a bearing between said lever and said yoke; and means for swinging said double lever so as to cause said yoke to assume any desired angular position relative to the axis of said shaft.

6. A combined lifting and propelling device for aircraft comprising: a drive shaft; a stub shaft the axes of said two shafts intersecting each other at an angle; a universal joint connecting said two shafts, said universal joint embodying two axes of rotation intersecting each other at the point of intersection of said two shafts; and a pair of blades extending oppositely outward along one of said axes of rotation; and means for varying the intersecting angle as said drive shaft rotates.

7. A propelling and lifting mechanism for aircraft comprising: a drive shaft; a bearing bracket member secured on the extremity of said drive shaft; a blade shaft journaled in said bracket member at right angles to the axis of said drive shaft and extending across and from opposite sides of the latter; a blade rigidly attached to said blade shaft at each side of said drive shaft; and means secured to said blade shaft within said bracket member for imparting an alternating rotation to said blade shaft as said drive shaft rotates so that said surfaces will assume different angles of incidence on opposite sides of said drive shaft as it revolves.

8. A propelling and lifting mechanism for aircraft comprising: a drive shaft; a bearing bracket member secured on the extremity of said drive shaft; a blade shaft journaled in said bracket member at right angles to the axis of said drive shaft and extending across and from opposite sides of the latter; a blade rigidly attached to said blade shaft at each side of said drive shaft so as to form a unitary structure therewith, said blades lying in planes substantially at right angles to each other, a yoke secured to said blade shaft within said bracket member; and means for holding said yoke at de- 75

sired angles so that as said drive shaft rotates so that said surfaces will assume different angles of incidence on opposite sides of said drive shaft as it revolves.

9. A combined lifting and propelling device for aircraft comprising: a bifurcated bearing bracket; a drive shaft for rotating said bearing bracket; a blade shaft journaled in and extending across the furcations of said bearing bracket;

blades carried on the opposite extremities of said blade shaft; a yoke straddling said blade shaft and hinged thereon between the furcations of said bracket; and means for maintaining said yoke at any desired angular position relative to the axis of said drive shaft.
